PELORUS

John R. Oliver, Beverly, Mass., assignor to United Shoe Machinery Corporation, Flemington, N. J., a corporation of New Jersey

Application July 20, 1945, Serial No. 606,047

2 Claims. (Cl. 33—72)

1

This invention relates to apparatus for use in making visual observations and is herein illustrated in its application to apparatus including a pelorus for use on shipboard. The invention is herein illustrated as embodied in an apparatus for use on the deck of a submarine to obtain relative bearings, or more specifically, to determine the angular relation between the lubber line of the submarine and the line of sight of the observer on an object or target.

It is an object of the present invention to provide an apparatus of this type which is readily adapted to the varying situations under which a pelorus is employed on the deck of a submarine and particularly to facilitate and expedite the manipulating of the pelorus under circumstances requiring the completion of observations in the shortest possible time. In taking the bearings of distant targets it is the usual practice to transmit to the control room of the submarine bearings of the target. In the illustrated apparatus this is accomplished by apparatus commonly known as the "Selsyn system" which is characterized by transmitting and receiving devices each provided with a single phase or single circuit field winding and a polyphase or polycircuit armature winding, the armature windings being interconnected. Such a system is disclosed in United States Letters Patent No. 1,612,117, granted December 28, 1926, on an application filed in the name of Hewlett et al. In the illustrated apparatus the Selsyn system is employed to transmit to the control room of the submarine the angular movement of the pelorus in azimuth. The receiving device in the control room operates a suitable instrument which indicates the line of sight of the pelorus.

In taking the bearings of armed enemy vessels within gun range of the submarine it is the usual practice to complete the computation of the position and course of the target from the deck station rather than to take the time required for accurate computation in the control room. Under such circumstances transmission of the angular movement of the pelorus to the control room is not required. It is an object of the present invention to facilitate the manipulation of the pelorus under such circumstances by providing an apparatus so organized that the pelorus may be operated independently of the Selsyn system when desired.

Accordingly, the present invention in one aspect thereof consists in the provision of apparatus comprising a sighting means or pelorus, a mount for said pelorus, a rotor on which said

mount is supported for free angular movement relatively to said rotor, and means for securing the mount to the rotor. In the illustrated apparatus the rotor is operatively connected to the transmitting devices of the Selsyn system. It will be understood that in securing the mount to the rotor the mount must have a predetermined orientation such that the angle of the line of sight of the pelorus agrees with the angle defined by the indicating means in the control room.

The invention also provides means for actuating the rotor to effect angular movement of the pelorus when the pelorus is secured to said rotor. In the illustrated organization the rotor is turned by a suitable actuator through transmitting means including elements translatable to change the ratio of the motion of the actuator to the motion of the rotor. This provides for an initial rapid motion of the pelorus in which it is quickly slewed into the general field of the target and a relatively slow motion of the pelorus to facilitate the manipulation thereof in bringing it to bear accurately on the target. To effect the change from high speed to low speed the invention provides means including translatable elements herein illustrated as gears which are shiftable to change the ratio of the motion of the actuator to the motion of the rotor and a second actuator operable to shift said gears.

The invention will now be described with reference to the accompanying drawings, illustrating the preferred embodiment thereof, and pointed out in the appended claims.

35 In the drawings,

Fig. 1 is a front elevation illustrating apparatus embodying the features of the present invention;

Fig. 2 is a section on the line II—II of Fig. 3 with the operating mechanism shown in full;

40 Fig. 3 is a section taken substantially on the line III—III of Fig. 2;

Fig. 4 is a side elevation, partly in section, illustrating the upper portion only of the apparatus;

45 Fig. 5 is an enlarged sectional elevation through the center of the apparatus illustrating a portion of the structure shown in Fig. 4; and

Fig. 6 is a detail view illustrating a cam plate which is manually operated to shift the gears which operate the pelorus.

The apparatus illustrated in the drawings is intended for use on the deck of a submarine and may be rigidly fixed to the deck or gimbal mounted similarly to the apparatus illustrated in

my copending application Serial No. 573,799, filed January 20, 1945.

Referring to Fig. 1, the numeral 10 indicates the base portion of a housing and the numeral 12 the upper portion of said housing which, as herein illustrated, provides a water-tight closure for operating mechanisms hereinafter described.

Referring to Fig. 2, a rotor herein illustrated as a vertical shaft 14 is journaled in a central bearing 16 formed in the upper portion 12 of the housing and said shaft is provided with a discoidal head 18 of relatively large diameter on which is mounted the sighting means or pelorus now to be described. Secured to the upper portion of the head 18 is a plate 20 having an upwardly extending marginal flange 22 on which the base portion of the pelorus is mounted for angular movement about an axis coinciding with the shaft 14. The plate 20 is centered on the head 18 by the engagement of a cylindrical boss 23 projecting upwardly from the head in a suitable counter bore in the plate. A cylindrical hub 24 (Fig. 5) projecting upwardly from the central portion of the plate 20 provides a bearing for the pelorus and the lower or base portion of said hub is of greater diameter than the upper portion in order to provide a shoulder 26 which serves as a support for the central portion of the pelorus. The pelorus is held against upward movement away from the plate 20 by a discoidal cap 28 secured by a screw 30 to the top face of the hub 24. Projecting upwardly and inwardly from the base 32 of the pelorus are arms 34 (Fig. 1) the upper portions of which provide bearings for a cross shaft 36 which provides a mounting for a clamping means in which a pair of binoculars may be mounted as indicated by broken lines in Fig. 1. Said clamping means comprises a jaw 38 mounted on the cross shaft 36 and pinned thereto to secure it against movement widthwise of the pelorus and a jaw 40 having a bifurcated lower portion 42 engaging plane faces at opposite sides of a sleeve 44 slidably mounted on the cross shaft 36, and pivotally mounted on a pin 46 extending through a downward extension of said sleeve. In order to locate the clamping assembly in a fixed position widthwise of the pelorus, collars 48 and 50 are secured to the cross shaft 36 at opposite sides of the head 52 of the right arm 34. The jaws 38 and 40 engage a cylindrical hinge portion of the binoculars centrally spaced between the eye pieces, the gripping surfaces of said jaws having the same curvature as said cylindrical portion of the binoculars. The jaws are normally held in their open position by a spring 54 seated in oppositely disposed sockets provided in portions of the jaws directly beneath their gripping surfaces. It will be understood that the spring 54 causes the right jaw 40 to swing in a clockwise direction, as seen in Fig. 1, about the pin 46, the left jaw 38 being rigidly maintained in a vertical position. For closing the jaws on the binoculars a finger lever 56 is pivoted at 58 to the lower or base portion of the jaw 38 and provided at its right end with a cam follower or stud 60 which engages a cam surface 62 in the forward branch of the right jaw 40. An angular arm 64 projects rearwardly and to the right from the central portion of the finger lever 56 and carries at its extremity a stud 66 (Fig. 4) which engages a cam surface in the rear branch of the jaw 40. During the counterclockwise movement of the finger lever 56, as viewed in Fig. 1, the studs 60 and 66 move upwardly along the cam surfaces causing the jaw 40 to swing into

gripping position. After the jaw has closed on the binoculars further movement of the finger lever causes the jaw 40 to swing in a clockwise direction about the binoculars moving the sleeve 44 to the left and compressing a spring 68 surrounding the cross shaft 36 and occupying the space between the left end of the sleeve and the base of a socket in the hub 70 of the jaw 38. When the finger lever 56 comes to the limit of its counterclockwise movement the studs 60 and 66 are seated in suitable recesses at the upper extremities of the cam surfaces, thus retaining the finger lever in said position. The construction and arrangement of the clamping mechanism is such that when the finger lever is at the limit of its counterclockwise movement the spring 68 exerts a continuing pressure against the left end of the sleeve 44, thus urging the jaw 40 in a counterclockwise direction about the studs 60 and 66 and thereby maintaining a continuous clamping pressure of the jaws against the binoculars. For turning the pelorus freely on the hub 24 of the plate 20 a pair of handlebars 78 project outwardly from the central portions of the arms 34 respectively. The cross shaft 36 rocks in its bearings in the arms 34 to permit movement of the binoculars in elevation. In order to limit such movement of the binoculars the hub of the jaw 38 has a downward extension 72 adjacent to the left arm 34, said extension terminating in a crosshead 74 (Fig. 4) which crosshead in turn terminates in lugs 76 which, as shown in Fig. 1, extend to the left for engagement with the upper portion of the arm 34 to limit the rocking movement of the binocular clamping assembly.

When it is desired to transmit to the control room of the submarine the angular movement of the binoculars in azimuth the binoculars are turned by rotating the shaft 14 and the rotation of said shaft is transmitted to synchronous generators 80 and 82 (Fig. 2) which transmit the angular movement of the binoculars to synchronous motors in the control room which operate indicating means which may be of any known type. In accordance with the usual practice in systems of this type one of the synchronous generators operates at a 1:1 ratio to the rotary movement of the shaft 14 and the other at a 36:1 ratio. As herein illustrated the generator 80 is operated at a 36:1 ratio by a large spur gear 84 on the reduced lower portion 86 of the shaft 14 operating through a pinion 88 and gear 90, the latter gear meshing with a pinion 92 on the generator shaft 94. The synchronous generator 82 is operated by a spur gear 96 meshing with a like gear 98 on the shaft 100 of the generator 82. For turning the shaft 14 there is provided an actuator herein illustrated as a rotor or wheel 102 the peripheral surface of which is generally frusto-conical in shape with the small diameter at the upper extremity of the wheel. For the convenience of the observer in turning the wheel a plurality of finger grips are provided on the wheel 102, said grips being herein illustrated as uniformly spaced radial projections one of which is identified by the numeral 104. Fixed to an inside shoulder in the upper portion of the wheel 102 is a ring 106 which is internally threaded for meshing engagement with a spur gear 108 fixed to a shaft 110 journaled in a bearing in a cylindrical block 112 secured to a head 114 in the upper portion of the top section 12 of the housing. The wheel 102 operates through connections now to be described to turn the shaft 14 at a 1:1 ratio to the

rotation of the wheel, or alternatively at a 1:12 ratio, the 1:1 ratio being employed in slewing the binoculars into the general field of the target and the 1:12 ratio being employed for slow motion of the shaft 14 to bring the binoculars accurately to bear on the target. In the illustrated organization the wheel is operatively connected to the shaft 14 by either of two trains of gears, each train including a gear shiftable between the meshing position and an idle position. Referring to Fig. 2 there are splined on the lower portion of the shaft 110 a small gear 116 and a relatively large gear 118, said gears being mounted on a common hub to facilitate the gear shifting operation. For turning the shaft 14 at a 1:12 ratio to the wheel 102 the small gear 116 meshes with a spur gear 120 fixed to a shaft 122 which has fixed to its reduced lower portion a pinion 124 which meshes with outwardly projecting teeth in a crown gear 126 secured to the reduced midsection of the shaft 14. The shaft 14 is operated at a 1:1 ratio by bringing the gear 118 into meshing engagement with inwardly projecting teeth of the crown gear 126. In Fig. 2 the gears 116 and 118 are shown in a neutral position with both gears out of meshing engagement with the gears on which they operate. For mounting the wheel 102 for rotary movement about an axis common to the shaft 14 the upper section 12 of the housing is provided with an endless rabbet 128 which serves as a track for the right angular portion 130 in the base of the wheel 102 and the upper portion of said wheel has an inwardly extending flange 132 which bears against a cylindrical surface of the housing 12 arranged concentrically to the shaft 14. For shifting the gears 116 and 118 into and out of meshing position a second actuator herein illustrated as a rotor or wheel 134 similar to the wheel 102 is mounted on the outer surface of the upper section 12 of the housing for rotary movement about an axis common to the shaft 14. As shown in Fig. 2 said ring is generally cylindrical and has a structure similar to an I-beam as seen in cross section. The wheel is supported by an outwardly projecting flange 136 of the housing 12 and is held against upward movement by gibbs 138 secured to the housing. Similarly to the wheel 102 the wheel 134 is provided with finger grips, herein illustrated as outward radial projections one of which is identified by the numeral 140. Referring to Fig. 6 the ring 134 has secured in a recess 142 in its inner surface a plate 144 having a cam track 146 in which travels the hemispherical head 148 (Fig. 3) of a stud 150 fixed in a head 152 at the free end of an arm 154 secured to one end of a cross shaft 156 journaled in bearings in the upper section 12 of the housing. Secured to the central portion of the cross shaft 156 are twin arms 158 projecting divergently from a common hub 160 pinned to said cross shaft. Swiveled in heads 162 at the free ends of the twin arms 158 are headed studs 164 which are slotted to receive marginal portions of the gear 118. It will be seen that rotary movement of the wheel 134 causes the cam plate 144 to swing the arm 154 thereby rocking the shaft 156 and swinging the twin arms 158 to move the gear 118 and with it the gear 116 vertically on the shaft 110.

In the illustrated apparatus the pelorus may be turned freely on the hub 24 by means of the handlebars 78 or, alternatively, the pelorus may be turned by means of the wheel 102 in which

case the angular movement of the binoculars in azimuth is transmitted to the control room of the submarine by means of the synchronous generators. In order that the indicating mechanism in the control room may accurately define the line of sight of the binoculars it is of course important that the binoculars be located with their line of sight in predetermined relation to the head 18 of the shaft 14 which actuates the synchronous generator. In the illustrated organization the correct registration of the pelorus relatively to the head of the shaft 14 is effected by the use of indexing means which enables the operator readily to effect a determinate orientation of the binocular mount on the head of the shaft 14. Said indexing means is herein illustrated as a key shown as an arm 206 (Fig. 5) pivotally mounted on a pin 208 in a bifurcated bracket 210 secured to the base 32 of the pelorus. The arm 206 operates in a slot 212 in an enlarged portion 214 of the flange 22 projecting upwardly from the plate 20 secured to the head of the shaft 14. In Fig. 5 the arm 206 is shown in its lowermost position wherein it is in registration with the slot 212. When it is desired to turn the pelorus freely on the hub 24 the arm 206 is lifted into a position in which its upper surface registers with an inclined surface 216 in the base of the pelorus, a suitable finger grip 218 being provided in the arm for convenient manipulation thereof. For yieldingly retaining the arm 206 in either its upper or its lower position a spring pressed roller 220 engages either the upper or the lower inclined surface of an angular boss 222 projecting outwardly from the arm 206. In the position of the arm illustrated in Fig. 5 the roller 220 engages the upper inclined surface 224 of the boss 222 thus yieldingly holding the arm against upward movement and retaining the arm in the slot 212. It will be understood that when the arm 206 is at the limit of its upward movement the roller 220 acts on the lower inclined surface of the boss 222 to hold the arm against downward movement. The roller 220 is placed in a bifurcated block 226 and mounted on a cross pin 228 which projects through said block and into longitudinal grooves 230 in an inclined bore in the base of the pelorus wherein the block 226 is slidably mounted. Thus, the block is held against rotary movement in the bore and the roller is maintained in proper angular relation to the boss 222. A spring 232 mounted in said bore and backed up by a short screw 234 yieldingly holds the roller 220 against the boss 222. In order to insure the movement of the pelorus with the shaft 14 without any play or vibration whatever means is provided for clamping the base of the pelorus to the plate 20 secured to the head 18 of said shaft. As shown in Fig. 5, said clamping means comprises jaws 236 and 238 constructed and arranged for gripping engagement with a circular flange 240 projecting upwardly from the plate 20. The jaw 236 is formed in the end portion of a sleeve 242 slidably mounted in a radial bore in the base 32 of the pelorus, said jaw having a hole concentric to said sleeve through which passes the threaded stem 244 of the jaw 236. Mounted for rocking movement in the sleeve 242 is a hollow shaft 246 which is internally threaded for operating engagement with the stem 244. For operating the shaft 246 a finger lever 248 is keyed to an outwardly projecting portion 250 of said shaft and retained thereon by a nut 252. Said nut also serves as a stop for the shaft 246, thus enabling said

shaft to impart a gripping force to the jaw 236 when the jaws are closed on the flange 240. The pressure of the sleeve 242 and the nut 252 against the finger lever when the jaws are closed on the flange 240 creates sufficient frictional resistance to turning movement of the finger lever to insure the maintenance of the jaws in gripping position until they are released by manual operation of the finger lever.

In order to protect the synchronous generators and the gearing from corrosion by contact with salt water when the submarine is submerged, all of the passages through which seepage of water might occur are sealed against water under pressure. To this end the joint between the housing sections 10 and 12 is sealed by a cylindrical gasket 168 (Fig. 2) mounted in a groove in a flange 170 projecting outwardly from the lower section 10 of the housing. To prevent seepage of water through the bearing of the shaft 14 in the housing 16 a garter spring seal, so called, is mounted in a recess 173 in the upper portion of the housing 16. The illustrated seal is a flexible cylindrical element 172 the outside diameter of which is substantially the same as the diameter of the recess 173, said element having a relatively thin inwardly projecting portion 175 frusto-conical in shape throughout the greater part of its extent and having in its margin a groove which receives an endless spring 171. The flexible element 172 is supported on a rigid discoidal member 179 surrounding the shaft 14 and seated in the recess 173 in the housing 16, said member having an upwardly extending tapered flange having a cylindrical surface which bears on the shaft 14 and a frusto-conical surface which receives all but the upper margin of the frusto-conical portion 175 of the flexible element. The bearing of the shaft 110 in the block 112 is sealed by a similar garter spring seal 174 mounted in a counter bore in said block. Referring to Fig. 3, the bearing of the rockshaft 156 in the upper section 12 of the housing is sealed by a garter spring seal 176. It will be seen that the opposite end of said shaft has its bearing in a socket in a cylindrical boss 178 projecting inwardly from the housing. It will be seen that the rockshaft 156 projects through a portion of the housing which is inwardly offset to provide space for the arm 154 between the housing and the wheel 134.

To enable the observer himself to determine the angle of the line of sight of the binoculars to the lubber line of the submarine a frusto-conical plate or dial 180 (Fig. 2) having punched out numerals indicating degrees of angulation is secured to an annular plate 182 which in turn is secured to the upper extremity of the housing. The plate 182 also serves to hold the wheel 102 against upward movement relatively to the housing. Referring now to Fig. 4, the angle of the line of sight of the binoculars is indicated on the dial 180 by a hair line on a transparent plate (not shown) mounted in a frame 184 projecting from an arm 186 and arranged in parallel relation to the dial 180. The arm 186 projects upwardly at an inclination toward the center of the pelorus to a bridge 188 connecting the outer ends of a pair of arms 190 projecting upwardly and outwardly from the pelorus. To enable the observer to read the angle of the line of sight of the binoculars on the scale 180 during total darkness a luminous substance is placed in a suitable cavity in a down-turned portion 192 of the arm 186 and covered by a transparent plate 193, the downturned portion 192 being so arranged that the luminous

substance is visible through the punched out numerals in the dial 180. To protect the plate 193 a cover 194 is hinged on the frame 184 and arranged to cover the transparent plate mounted in said frame. When the scale is in use the cover 194 is held in a retracted position by a spring clip 196 on the arm 186.

For observing targets or other objects within the range of the observer's vision the observer may employ sight vanes 198 and 200 (Fig. 4) mounted on the pelorus and arranged to define a line having the same position in azimuth as the line of sight of the binoculars. The rear sight 200 is mounted on the bridge 188 and the forward sight 198 is mounted in a bracket 202 in the central portion of a bridge 204 (Fig. 1) in the forward portion of the pelorus.

The illustrated device has numerous uses chief among which is taking bearings of targets such as enemy vessels and transmitting to the control room of the submarine the angular position of the binoculars in azimuth when they are sighted on the target. The usual procedure in manipulating the binoculars when they are connected to the synchronous generators for transmission of their angular movement to the control room is as follows. First, the wheel 134 is operated, if necessary, to bring into operation that train of gears providing for the operation of the shaft 14 by wheel 102 at a 1:1 ratio. Thereupon the wheel 102 is operated to bring the binoculars into the general field of the target. The wheel 134 is then turned to bring into operation the other train of gears providing for rotation of the shaft at a 1:12 ratio. The operator then manipulates the binoculars with one hand in order to maintain a proper position of the line of sight in elevation while turning the wheel 102 with the other hand to swing the binoculars in azimuth with a slow and uniform motion until they are brought to bear upon the target. When the binoculars are sighted on the target a signal is given to the control room or to the torpedo room by means of a suitable voice tube or by means of an electrically operated buzzer operated by a switch conveniently located for operation by the observer. Under certain circumstances, particularly when the target is an armed enemy vessel within gun range of the submarine, it is desirable for the observer himself to take the bearing of the target and, after making the necessary computations of the speed and direction of the target and the distance of the target from the submarine, to give final directions through the voice tube for the firing of torpedoes. In this case the pelorus is disconnected from the head of the shaft 14 by operation of the finger levers 206 and 208 and the handle-bars 78 are employed to bring the binoculars, or the sight vanes 198 and 200 to bear on the target. After the target is sighted the observer reads the bearing on the frusto-conical dial 180, then makes the necessary computations as above stated, and gives his orders through the voice tube.

While the illustrated apparatus is intended mainly for observations during the hours of darkness when it is difficult or impracticable to make observations by means of a periscope, the apparatus is also useful in making routine observations when the submarine is traveling on the surface during daylight hours. Such observations would include not only observing possible targets but also taking the bearings of land marks or other objects for purposes of navigation.

Having thus described my invention, what I

claim as new and desire to secure by Letters Patent of the United States is:

1. Apparatus comprising a standard for a sighting instrument, a rotor on which said standard is mounted for free angular movement relatively to said rotor, means for securing the standard against such free angular movement, a first wheel mounted to rotate on an axis common to the axis of said rotor, two trains of gears for alternatively connecting said first wheel to said rotor thereby to actuate said rotor at two different speeds relatively to said first wheel, a water-tight housing in which said two trains of gears are mounted, each train of gears including a gear shiftable between a meshing position and an idle position, a second wheel mounted on said water-tight housing for rotation on an axis common to the axis of said rotor, a cam fixed to the concave surface of said second wheel, and means for shifting said shiftable gears comprising shifters mounted within said housing, a shaft on which said shifters are mounted, said shaft having a portion projecting outwardly from the housing, a water-tight bearing in the housing in which bearing said shaft is journaled, an arm fixed to that portion of said shaft projecting outwardly from the housing, and operating means between said arm and said cam, a portion of the housing being offset inwardly to provide a space between the housing and the second wheel within which said arm operates.

2. Apparatus comprising a standard for a sighting instrument, a rotor on which said standard is mounted, a first wheel mounted to rotate on an axis common to the axis of said rotor, two trains of gears for alternatively connecting said first wheel to said rotor thereby to actuate said rotor at two different speeds relatively to said first wheel, a water-tight housing in which said two trains of gears are mounted, each train of gears including a gear shiftable between a meshing position and an idle position, a second wheel mounted on said water-tight housing for rotation on an axis common to the axis of said rotor, a cam fixed to the concave surface of said second

5

10

wheel, and means for shifting said shiftable gears comprising shifters mounted within said housing, a shaft on which said shifters are mounted, said shaft having a portion projecting outwardly from the housing, a water-tight bearing in the housing in which bearing said shaft is journaled, an arm fixed to that portion of said shaft projecting outwardly from the housing, and operating means between said arm and said cam, a portion of the housing being offset inwardly to provide a space between the housing and the second wheel within which said arm operates.
